RELAY DEVICE

Paul L. Betz, Baltimore, Md., assignor to Consolidated Gas Electric Light and Power Company of Baltimore, Baltimore, Md., a corporation of Maryland

Application August 31, 1934, Serial No. 742,335

17 Claims. (Cl. 175—320)

This invention relates to relay devices and more particularly to relay devices wherein the operation of the relay contacts is delayed for a predetermined period after current is first supplied to said relay. Devices embodying the invention may be used for various purposes, and for purposes of illustration a device is hereinafter described for use with a gas heater but it will be understood that the invention is not limited to 10 this particular application.

It has been proposed to ignite gas burners for water heaters and the like by means of electric pilots comprising devices heated electrically to a temperature sufficient to ignite the gas. In such devices it is desirable that the gas supply to the burner shall not be turned on until the electric pilot device has been heated to the requisite temperature to ignite the gas, and a relay device embodying the invention can be employed for 15 this purpose in combination with a suitable electric pilot device and an electrically operated valve controlling the gas supply. Electric pilot devices, and also electrically operated valves such as solenoid valves opened by energization of a 20 solenoid and closed by gravity when the solenoid is de-energized, are known and can be obtained on the market and hence will not be described specifically herein.

One of the objects of the invention is to provide a novel relay device wherein a time delay or lag is introduced between the energization of the relay and the operation of the relay contacts.

Another object is to provide a relay device of the type characterized that is dependable in operation and is of such construction that failure of any of its electrical circuits or of the power supply will result in a return of the relay contacts to the de-energized position of the relay.

Another object is to provide a relay device of the type characterized that is of rugged construction, simple in design and inexpensive to manufacture.

A further object is to provide a novel metallic structure providing a supporting frame and a magnetic path for relay devices of the type characterized.

A still further object is to provide a relay device wherein the armature that operates the relay contacts is not actuated by the magnetic field until an auxiliary time-delay device operates to effect initial movement of the armature.

Another object is to provide a device of the type characterized wherein an electrically heated device is employed to bring the relay device into operation after current is supplied thereto whereupon said device is automatically de-energized.

These and other objects will appear more fully hereinafter as the description proceeds.

Two embodiments of the invention have been illustrated in the accompanying drawing but it is to be expressly understood that said drawing is for purposes of illustration only and is not to be construed as a definition of the limits of the invention, reference being had to the appended claims for this purpose.

In said drawing,

Fig. 1 is a perspective view of a device embodying the invention;

Fig. 2 is a sectional view of the device shown in Fig. 1;

Fig. 3 shows a metallic element which may be 15 bent into a desired form for the magnetic circuit of the device;

Fig. 4 is a wiring diagram of the device shown in Figs. 1 and 2; and

Fig. 5 is a wiring diagram of another device 20 embodying the invention.

While as respects many aspects of the invention the metallic structure of the device may have any suitable or desired form, Figs. 1 and 3 illustrate a simple but efficient and practical means for forming this structure. Fig. 3 illustrates a metallic blank cut to the particular configuration shown which includes the three plate-like portions 1 connected by intermediate strips or necks 2 each of which is provided with an opening 3, preferably circular in form. This blank may be formed into the desired metallic structure by bending on the dotted lines 4 into the shape shown in Fig. 1 wherein the plates 1 constitute spaced parallel sides that are connected by top and bottom necks 2 having the aligned openings 3. After the device has been completely assembled as hereinafter described, the two adjacent plates 1 may be secured together in any suitable manner as by riveting.

Referring now to Figs. 1 and 2, the magnet coil or winding 5 is formed on a tube 6 of suitable non-magnetic material, the length of the winding being less than that of the tube 6 and the winding being located closely adjacent one end of the tube. The holes 3 in the necks 2 are of sufficient size to permit the insertion of the tube 6. After the coil 5 has been placed on the tube 6, and before the metallic blank is formed as shown in Fig. 1, the longer unobstructed end of the tube is inserted in the opening 3 of the lower neck 2 and then the blank is formed about the tube as described above, the upper end of the tube being inserted in the opening 3 of the upper neck during the forming operation. The tube 6 may be secured in the openings 3 in any suitable way, if desired, as by a force fit.

Within the tube 6 is an armature 7 of suitable magnetic material and of cylindrical shape as shown in the drawing. The armature 7 is se-

cured in any suitable manner to a rod 8 of suitable non-magnetic material which extends throughout the tube 6 and projects from the ends thereof, said rod passing through openings in 5 stop and guide members 9 and 10 that are secured in the ends of the tube 6 in any suitable manner as by means of set screws 11. The armature 7 and rod 8 are thus free to move as a unit in the tube 6, such movement being guided by 10 the members 9 and 10 to prevent binding or sticking of the armature on the tube wall. The limits of movement of the armature can be adjusted by suitable projections on the rod 8 which as shown comprise stop nuts 12 and 13 threaded on said 15 rod and adjustable thereon.

Suitable contact making and breaking means are provided for actuation by the operating rod 8 on movement of the armature 7, and such means are preferably mounted at one end of the 20 frame by means of a block 14 of any suitable material which is secured between the side plates 1 of the frame by means of screws 15. In the form shown, the relay is provided with a pair of normally closed contacts 16, 17 and a pair of 25 normally open contacts 18, 19. The contacts 16, 17 are carried respectively by resilient conductive strips 20 and 21 of any suitable material which are mounted on the block 14 in any suitable way as by clamping the same between said block and 30 additional clamping blocks 22, which are secured to the block 14 by means of screws 23. The normally open contacts 18, 19 are respectively carried by resilient conductive strips 24 and 25 which are mounted on the block 14 in the same 35 manner as the strips 20, 21. The strip 24 is provided with a yoke 26 which straddles the operating rod 8 and with a finger 27 which normally bears on the strip 21 and maintains contacts 16, 40 17 closed. It will be seen that the contacts 16, 17 will be opened and the contacts 18, 19 will be closed by upward movement of the armature 7 and rod 8, said rod being provided with suitable means for engaging and lifting the yoke 26 which in the form shown comprises the stop 45 nut 13.

The armature 7 is shown in Fig. 2 in the position which it assumes when the device is de-energized and in this position the armature does not project sufficiently within the coil 5 for actuation by the magnetic field generated by said coil. Any suitable means may be provided 50 whereby the armature tends to assume this position, but when the device is so positioned that the armature moves vertically as shown in the drawing, gravity alone will ordinarily suffice to insure that the armature always returns to the position shown when the coil is de-energized and that the contacts always assume the condition 55 shown in Fig. 2. Hence when the current is supplied to the coil 5, the relay will not operate and in accordance with the invention an auxiliary device having time-delayed operation is provided for moving said armature initially from the position shown in Fig. 2 into the range where- 60 in it can be actuated by the magnetic field of the magnet coil. While from many aspects of the invention any suitable type of time-delayed device may be employed for this purpose, the invention is preferably embodied in a tempera- 65 ture responsive device which is electrically heated to effect the desired initial movement of the armature. Preferably the heating current is interrupted when this initial movement is effected in such a way as not to interfere with continued 70 action of the relay by providing the heating cir-

cuit with relay contacts which are opened by movement of the armature and by connecting this circuit in parallel with the electromagnet winding. As shown, this temperature responsive element comprises a bimetallic strip 28 surrounded by a heating coil 29 and mounted on the frame in any suitable manner as by means of a block 30 secured between the side plates 1 by means of screws 31. The end of the bimetallic strip is fastened to the block 30 by screws 32 10 and the strip is so arranged that on heating its forked end 33 will rise to engage an adjustable abutment such as a nut 34 on the rod 8 and thereby to lift the armature 7 sufficiently that it comes within the range of actuation by the 15 magnetic field.

Fig. 4 illustrates a wiring arrangement of the device which is suitable for the purpose mentioned above of controlling the operation of a gas water heater having an electric pilot device. 20 Current is supplied to the relay terminals 35, 36 and the heating circuit including in series the coil 29 and the normally closed relay contacts 16, 17 is connected across said terminals in parallel with the electromagnet coil. A wire 25 37 leads from terminal 35, to which one end of said heating circuit is connected, to the coil 5 of the electromagnet and a wire 38 leads from the other end of the coil to one of a pair of terminals 39 across which is connected a suitable electric 30 ignition device indicated diagrammatically at 40. The other terminal 39 is connected to terminal 36 by a wire 41 whereby both the coil 5 and the pilot device 40 are energized as soon as and as long as current is supplied to the relay. 35 The heating circuit is completed to the terminal 36 by connecting the end of the heating coil 29 to any desired point in the circuit from the coil 5 to the terminal 36. The normally open relay contacts 18, 19 may be used to control an external 40 energizing circuit (not shown) such as the circuit of the electrically operated gas supply valve referred to above.

Because the armature 7 occupies the position shown in Fig. 2 when current is first supplied to the relay, said armature is not lifted by energization of coil 5 and hence contacts 18, 19 are not closed to open the gas supply to the burner. Heating coil 29 is energized simultaneously with magnet coil 5, however, and as soon as the bimetallic strip has been heated sufficiently, the armature 7 will be lifted by the strip sufficiently to bring it within the range of actuation by the magnetic field of the coil 5 whereupon the armature will be drawn upward by said magnetic 55 field until the stop nut 12 engages the stop member 9. During this movement of the armature, the stop nut 13 engages yoke 26 with the result that contacts 18, 19 are closed to open the gas supply to the main burner whereas contacts 16, 60 17 are opened to de-energize the heating coil 29. The armature 7, however, is held in its upper position by the magnetic field of the coil 5 until the relay is de-energized, whereupon it returns by gravity to the position shown in Fig. 2, thereby 65 restoring the relay contacts to their initial position ready for a further operation.

Instead of supplementing the magnetic field by the lifting action of the bimetallic strip as described above, the action of the bimetallic strip or other time-delay device can be employed to regulate the circuits of supplementary windings, as for example to shunt a winding opposed to the coil 5 or to energize a winding assisting the coil 5. For example, a supplementary mag- 75

netic field may be established by the operation of a suitable time-delay device, the combined fields being sufficient to move the armature initially. The movement of the armature may then be employed to effect the de-energization of the supplementary field. The supplementary winding may be separate from or mounted with the main coil 5 described above, and the movement of the strip 28 may be employed to close 10 suitable contacts in the circuit of the supplementary winding, the heating circuit for the strip 28 being preferably established in parallel with the coil 5 as above described.

Fig. 5 is a diagram of an arrangement of this 15 type which is generally similar to Fig. 4, corresponding numerals being used to designate corresponding elements. Fig. 5 also includes, however, a supplementary winding or coil 42 in shunt with the coil 5, and a pair of normally 20 open contacts 43, 44 in series with said supplementary winding 42. Heating of the strip 28, which is arranged to operate contacts 43, 44 instead of to lift the armature, causes the strip to bend and close said contacts whereby the supplementary winding 42 is energized. The armature is normally in the position shown in Fig. 2 25 beyond the range of actuation of the coil 5. Hence the armature will not be moved when current is first supplied to the relay, but when 30 the magnetic field is strengthened by the energization of the supplementary winding, the combined field is sufficient to lift the armature and operate the contacts 16, 17 and 18, 19 as above described. The strip 28 then cools off and contacts 35 43, 44 separate, the supplementary winding being thereby de-energized but the armature being held in advanced position by the field of the coil 5.

It will be seen that the relay described above 40 interposes a time delay or lag between the time when current is first supplied thereto and the time of actuation of the armature to change the condition of the relay contacts. As described above, this time delay can be utilized to insure 45 that the electric pilot device is heated to a temperature sufficient to ignite the gas before the gas supply is turned on. It will further be understood, however, that this operation constitutes only one of the many uses to which the device 50 can be put. The device is simple and inexpensive but at the same time of rugged construction and reliable in operation, requiring no skilled labor for installation and maintenance. Further, no delicate adjustments are involved 55 so that the likelihood of the device getting out of order is reduced to a minimum.

While several embodiments of the invention 60 have been described and illustrated in the drawing, it is to be expressly understood that the invention is not limited thereto but is capable of a variety of mechanical expressions many of which will now appear to those skilled in the art, and that changes may be made in the form, details of construction and arrangement of the 65 parts, and suitable equivalent elements substituted for those specifically illustrated, without departing from the spirit of the invention. Other methods for initiating the movement of the relay armature, involving further arrangements of windings and contacts for controlling 70 the same, will also readily occur to those skilled in the art and are included within the spirit and scope of the invention. Reference is therefore to be had to the appended claims for a definition 75 of the limits of the invention.

What is claimed is:

1. In a relay, the combination of a contact making and breaking device, an electromagnet having a movable armature for operating said device, said armature occupying a position when the relay is de-energized in which it cannot be actuated by the magnetic field, a temperature-responsive element heated when the relay is energized for moving said armature to a position where it is actuated by the magnetic field 10 of said electromagnet, and electrical heating means for said element connected in parallel with said electromagnet, said parallel circuit including normally closed relay contacts which are opened on movement of said armature by the 15 magnetic field.

2. In a relay, a contact making and breaking device, an electromagnet having an armature movable axially of the magnet coil for operating said device, said armature occupying a position 20 when the relay is de-energized wherein it cannot be actuated by the magnetic field, a temperature-responsive element for moving said armature initially into the range of actuation by said electromagnet, electrical heating means for 25 said element, and a circuit for energizing said heating means upon energization of said electromagnet and de-energizing said heating means upon operation of said device.

3. In a relay, a contact making and breaking 30 device, an electromagnet having an armature movable axially of the magnet coil for operating said device, said armature occupying a position when the relay is de-energized wherein it can- 35 not be actuated by the magnetic field, a tem- perature-responsive element for moving said armature initially into the range of actuation by said electromagnet, and electrically heating means for said element, said heating means being connected in parallel with said electromag- 40 net and said parallel circuit including relay contacts which are opened on movement of said armature by said magnetic field.

4. In a relay, the combination of a contact 45 making and breaking device, an electromagnet having a coil, an armature for operating said device, said armature being movable axially of said coil and tending to occupy by gravity a position in which it cannot be actuated by the magnetic field, a bimetallic strip for moving said armature to a position within its range of actuation by the magnetic field, and a coil for heating said strip, the energizing circuit of said coil including normally closed relay contacts which are 50 opened when the armature is actuated by the 55 magnetic field.

5. In a relay device of the class described, the combination of a frame, a solenoid coil mounted vertically thereon, an armature having a lowermost position beyond the range of actuation by 60 the magnetic field, a bimetallic strip operatively connected with said armature to lift the same into said range, a heating coil for said strip, the energizing circuit for said coil including normally closed relay contacts, a pair of normally 65 open relay contacts, and contact operating means actuated by movement of said armature within said range to open said closed contacts and to close said open contacts.

6. In a relay device of the class described, the 70 combination of a magnetic circuit comprising spaced parallel side plates, a solenoid coil disposed within said plates, an armature having a lowermost position beyond the range of actuation by the magnetic field, a bimetallic strip 75

mounted between said plates and operatively connected with said armature to lift the same into said range, a heating coil for said strip, the energizing circuit for said coil including normally closed contacts, a pair of normally open contacts, said contacts being mounted between said plates, and contact operating means connected to said armature.

7. In a relay, the combination of a contact making and breaking device, an electromagnet having a movable armature for operating said device and tending to occupy a position wherein it cannot be actuated by the magnetic field, a supplementary electromagnetic means operative to cause initial movement of said armature into the range of actuation by said electromagnet, and temperature-responsive means for controlling the circuit of said supplementary means.

8. In a relay, the combination of a contact making and breaking device, an electromagnet having a movable armature for operating said device and tending to occupy a position wherein it cannot be actuated by the magnetic field, a supplementary electromagnetic means operative to cause initial movement of said armature into the range of actuation by said electromagnet, a temperature-responsive device controlling the circuit of said supplementary means, and electrical heating means for said temperature-responsive device.

9. In a relay, a contact making and breaking device, an electromagnet having an armature movable axially of the magnet coil for operating said device, said armature occupying a position when the relay is de-energized wherein it cannot be actuated by the field of said electromagnet, a supplementary electromagnetic means operative to cause initial movement of said armature into the range of actuation by said electromagnet, and temperature-responsive means for controlling the circuit of said supplementary means.

10. In a relay, a contact making and breaking device, an electromagnet having an armature movable axially of the magnet coil for operating said device, said armature occupying a position when the relay is de-energized wherein it cannot be actuated by the field of said electromagnet, a supplementary electromagnetic means operative to cause initial movement of said armature into the range of actuation by said electromagnet, a temperature-responsive device controlling the circuit of said supplementary means, and electrical heating means for said temperature-responsive device.

11. In a relay, a contact making and breaking device, an electromagnet having an armature movable axially of the magnet coil for operating said device, said armature occupying a position when the relay is de-energized wherein it cannot be actuated by the field of said electromagnet, a supplementary electromagnetic means operative to cause initial movement of said armature into the range of actuation by said electromagnet, a temperature-responsive device controlling the circuit of said supplementary means, and electrical heating means for said temperature-responsive device, said heating means being connected in parallel with said electromagnet and said parallel circuit including relay contacts which are opened by movement of said armature.

12. In a relay, a contact making and breaking device, an electromagnet having an armature

movable axially of the magnet coil for operating said device, said armature occupying a position when the relay is de-energized wherein it cannot be actuated by the field of said electromagnet, a supplementary electromagnetic means operative to cause initial movement of said armature into the range of actuation by said electromagnet, a temperature-responsive device controlling the circuit of said supplementary means, and electrical heating means for said temperature-responsive device, said heating means being connected in parallel with said electromagnet and said parallel circuit including relay contacts which are opened by movement of said armature, said supplementary means also being connected in parallel with said electromagnet in a circuit including relay contacts operated by said temperature-responsive device.

13. In a relay, a contact making and breaking device, an armature for operating said device, an electromagnet, said armature occupying a position when the relay is deenergized wherein it cannot be actuated by said electromagnet, means having time-delayed operation for supplementing the action of said electromagnet to cause initial movement of said armature into the range of actuation by said electromagnet, and a relay circuit for energizing said means and including a make and break device operated by said armature.

14. In a relay, a pair of contacts, an electromagnet having a movable armature for closing said contacts and tending to occupy a position wherein it cannot be actuated by the magnetic field, supplementary means operative to cause initial movement of said armature into the range of actuation by said electromagnet, and a relay circuit including normally closed contacts for energizing said means, said normally closed contacts being adapted to be opened on movement of said armature and said means having time-delayed operation.

15. In a relay, the combination of a pair of contacts, an electromagnet having an armature for closing said contacts and tending to occupy a position in which it cannot be actuated by the magnetic field, temperature-responsive means operative to cause initial movement of said armature into the range of actuation by said electromagnet, an electric heating element for said means, and a pair of normally closed contacts in circuit with said element and adapted to be opened by said armature.

16. In a relay, the combination of a make and break device, an electromagnet, a movable armature for operating said device and tending to occupy a position in which it cannot be actuated by the magnetic field, supplementary electrical means having time-delayed operation for causing initial movement of said armature into the range of actuation by said electromagnet, and a relay circuit for said supplementary means that is independent of said make and break device.

17. In a relay, the combination of a make and break device, an electromagnet, a movable armature for operating said device and tending to occupy a position in which it cannot be actuated by the magnetic field, supplementary electrical means having time-delayed operation for causing initial movement of said armature into the range of actuation by said electromagnet, and a relay circuit for said supplementary means that is in parallel with said electromagnet.
